CLAIM

The ornamental design for a cat litter box as shown and described.

DESCRIPTION

FIG. 1 is a front, top, and left perspective view of a cat litter box showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear, bottom, and right perspective view thereof; and,

FIG. 9 is a perspective view of the cat litter box of FIG. 1 in use.

The broken lines shown in the drawings represent portions of the cat litter box that form no part of the claimed design.

1 Claim, 9 Drawing Sheets
